(57) **CLAIM**

The ornamental design for a liquid crystal display (LCD) for operating the state of home appliances with graphical user interface, as shown and described.

DESCRIPTION

FIG. 1 is a front, top and right side perspective view of a liquid crystal display (LCD) for operating the state of home appliances with graphical user interface, showing our new design;

FIG. 2 is a front view thereof;

FIG. 3 is a rear view thereof;

FIG. 4 is a left side view thereof;

FIG. 5 is a right side view thereof; and,

FIG. 6 is a top plan view thereof.

The broken line showing in FIGS. 1-6 of a tablet type computer illustrates the environment of the article of manufacture. The broken line showing in FIGS. 1 and 2 of a display panel or screen, and text, illustrates portions of the article of manufacture. None of the broken lines form part of the claimed design.
